CLAIM

We claim the ornamental design for a dish brush, as shown and described.

DESCRIPTION

FIG. 1 is a perspective view of the dish brush of the present invention.

FIG. 2 is a front elevation view of the dish brush of the present invention.

FIG. 3 is a rear elevation view of the dish brush of the present invention.

FIG. 4 is a left side elevation view of the dish brush of the present invention.

FIG. 5 is a right side elevation view of the dish brush of the present invention.

FIG. 6 is a top plan view of the dish brush of the present invention; and,

FIG. 7 is a bottom plan view of the dish brush of the present invention.

The broken lines illustrate features of the dish brush that form no part of the claimed design.
